UNITED STATES PATENT OFFICE

WILLIAM E. KAVENAGH, OF AKRON, OHIO, ASSIGNOR TO THE GOODYEAR TIRE & RUBBER COMPANY, OF AKRON, OHIO, A CORPORATION OF OHIO

DESIGN FOR A SHOE SOLE

Application filed July 21, 1931. Serial No. 40,814. Term of patent 3½ years.

To all whom it may concern:

Be it known that I, WILLIAM E. KAVENAGH, a citizen of United States, residing at Akron, in the county of Summit and State of Ohio, have invented a new, original, and ornamental Design for a Shoe Sole, of which the following is a specification, reference being had to the accompanying drawings, forming part thereof.

Fig. 1 is a bottom plan view of a shoe sole showing my new design; and

Fig. 2 is a cross-sectional view taken on line II—II of Fig. 1.

I claim:

The ornamental design for a shoe sole, as shown.

WILLIAM E. KAVENAGH.
